[57] CLAIM

The ornamental design for a food tray, as shown and described.

DESCRIPTION

FIG. 1 is a top perspective view of a food tray showing my new design;

FIG. 2 is a top plan view thereof;

FIG. 3 is an enlarged cross-sectional view taken along a line and viewed in the direction of the arrows 3—3 of FIG. 2.

FIG. 4 is a side elevational view thereof from the right side of FIG. 2;

FIG. 5 is an end elevational view thereof from the bottom of FIG. 2;

FIG. 6 is an end elevational view thereof from the bottom of FIG. 7; and

FIG. 7 is a bottom plan view thereof.
